UNITED STATES PATENT OFFICE.

ALBERT E. PAINTER AND WATERFIELD PAINTER, OF RENO, NEVADA.

ROTARY INTERNAL-COMBUSTION ENGINE.

1,238,806.

Specification of Letters Patent.

Patented Sept. 4, 1917.

Application filed June 30, 1916. Serial No. 106,893.

To all whom it may concern:

Be it known that we, ALBERT E. PAINTER and WATERFIELD PAINTER, citizens of the United States, residing at Reno, in the 5 county of Washoe and State of Nevada, have invented new and useful Improvements in Rotary Internal-Combustion Engines, of which the following is a specification.

This invention relates to rotary internal 10 combustion engines, the object in view being to produce a simple and compact engine employing in combination with a stationary member formed with an annular combustion chamber and a segmental compression chamber, a rotary member arranged at one side 15 of the stationary member and carrying laterally slidable abutments which operate within the compression and combustion chambers in such manner that the explosive mixture is compressed by being forced and transferred from the large central chamber 20 of the stationary member through a pass into the combustion chamber in which it is ignited thereby expanding and driving the 25 movable abutment in a circular path around and within the combustion chamber.

A further object of the invention is to provide means to compensate for expansion of the metal parts which may occur when 30 the engine becomes heated after continued operation and under adverse atmospheric conditions.

With the above and other objects in view, the invention consists in the novel construction, combination and arrangement of parts, 35 as herein described, illustrated and claimed.

In the accompanying drawings:

Figure 1 is an inside face view looking 40 toward the meeting face of the stationary member of the engine, showing the compression and combustion chamber.

Fig. 2 is a similar view of the rotary member of the engine, illustrating the compressing and power abutments and also the 45 passages.

Fig. 3 is a diametrical section through the engine.

Fig. 4 is a side elevation of the same.

Fig. 5 is a detail view illustrating the 50 compensating means.

The main stationary and rotary parts of the engine are indicated respectively at 1 and 2, said members being substantially circular or disk-like and arranged side by 55 side, the meeting faces of the members 1 and 2 fitting closely together along the line

3 in Fig. 3. The stationary member, or what may be termed the casing of the engine, is provided with an enlarged supporting base 4.

In Fig. 1, which represents an inside face view of the stationary member or casing 1, it will be observed that said member is formed with an annular channel adjacent to the outer margin thereof constituting a 60 combustion chamber 5. At the outer and inner sides of the combustion chamber 5, the member 1 is formed with concentric annular grooves 6 to receive packing rings 7 for the purpose of holding compression. 65 Each of the rings 7 is preferably of the split resilient type. The rotary member or rotor 2 is likewise provided with annual concentric grooves 8 to receive the opposite lateral portions of the same packing rings 70 7 when the two members 1 and 2 are placed together in the relation illustrated in Fig. 3.

The stationary member 1 is also formed with a compression chamber 9 substantially semi-circular as shown in Fig. 1 and terminating in inclines 10 which lead to and from an abutment retracting surface 11 which is flush with the meeting face of the sections 1 and 2. The stationary member 1 is provided at a suitable point in the length 80 of the combustion chamber 5 with a stationary abutment 12 having an inclined surface upon which the power abutment rides once in each revolution of the rotor or rotary member 2. 13 represents a spark plug entering the combustion chamber 5, and 14 the exhaust port which leads out through the periphery of the stationary member 1.

The rotor 2 is mounted transversely movable on a sliding key way 38 on the engine 95 shaft 15, the latter being journaled in suitable bearings (not shown). The shaft 15 also passes through a central opening 16 in the stationary member 1 and is formed with a longitudinal bore 17 for admitting the explosive mixture to the engine. A passage 18 leads from the bore of the shaft 15 to an inlet passage 19 in the meeting face of the member 2 as illustrated in Fig. 2. The member 2 is also formed with a passage 20 100 having an inlet port 21 and an outlet port 22, said ports being arranged respectively at the inner and outer sides of the inner packing ring 7, the port 21 communicating with the compression chamber 9 and the port 22 110 communicating with the combustion chamber 5. It is to be understood that the

meeting face of the rotor is flat or plane with the exception of the several ports just referred to and the guide ways 23 and 24 for the power abutment 25 and the compressing abutment 26, respectively, and concentric annular grooves 8. The compressing abutment 26 is pressed into the compression chamber 9 of the stationary member 1 by means of one or more backing springs 27 and the power abutment 25 is pressed toward and into the combustion chamber 5 by means of one or more backing springs 28. The member 2 is formed with offset chambers 29 and 30 to admit of the movement of the abutments 25 and 26 transversely with respect to the members 1 and 2.

In order to provide for expansion in case of the heating of the engine, we employ the compensating means illustrated in detail in Fig. 5, wherein it will be seen that the rotor 2 is provided with a sliding key way allowing rotor 2 to move transversely on shaft 15 and near the center of its outside face with a circular bearing face 31. Working in contact therewith is a thrust collar 32 which is pressed against the collar 31 by means of a coiled expansion spring 33 interposed between the collar 32 and another collar 34 which is fixed in relation to the shaft 15. Bolts 35 extend from the thrust collar 32 through openings in the collar 34 and are threaded to receive tensioning nuts 36 which bear against the outer face of the collar 34. In case of excessive expansion of the metal parts due to heat, the rotor 2 is thus enabled to yield away from the stationary member 1 while at the same time the rings 7 hold compression, and suitable stuffing material used where rotor 2 slides transversely on shaft 15 to prevent leakage at that point.

In order to supply explosive mixture to the engine, a stationary supply pipe 37 is connected to the outer end of the engine shaft 15 by means of a union 38 containing suitable stuffing material which will prevent leakage at that point.

From the foregoing description, taken in connection with the accompanying drawings, the operation of the engine will now be understood to be as follows: The transversely slideable and spring pressed abutment 26, in moving in its circular path, passes from the surface 11 into one end of the compression chamber 9 thereby drawing in explosive mixture through the port 19, passage 18 and the bore 17 of the shaft 15.

At the same time the charge of explosive mixture which was previously drawn in as just described and is ahead of the compression abutment 26, is forced thereby in the course of its rotation through port 21, passage 20 and port 22 into explosion chamber 5, and when port 21 is closed by passing from chamber 9 to surface 11, then or there-

after the mixture is exploded by spark at plug 13, which is produced by a jump spark coil and battery operated by a commutator revolving with the shaft and timed to deliver a spark as indicated before, also by shifting the computator relative to the shaft the time of sparking may be advanced or retarded. Any other arrangement such as make and brake system or magneto ignition with proper connections can also be used. The explosive mixture expanding between the stationary abutment 12 and the moving abutment 25 causes rotor 2 to revolve. The burned gases ahead of the power abutment 25 are forced outwardly through the exhaust port 14 by the scavenging action of said power abutment 25. The abutment 25 then rides upwardly on the inclined surface of the stationary abutment 12 and is again pressed into the combustion chamber 5 by the springs behind said abutment. Therefore, in each complete revolution of the engine, the compressing abutment 26 moves throughout the entire length of the compression chamber, drawing in one charge of mixture and forcing another charge into the combustion chamber, in the same revolution, the power abutment 25 makes one complete circuit of the combustion chamber 5, being propelled by the expansion of the explosive mixture and acting to scavenge the burned gases in advance thereof. Any cooling and lubricating system may be employed in connection with the engine, and it will also be understood that the parts hereinabove described constitute merely one power unit, it being perfectly feasible to employ as many of such power units as may be needed in combination with a common engine shaft. For example, two rotors may be used in connection with a central intervening stationary member 1, by duplicating the engine already described on the reverse side of stationary member 1 on the same shaft, and in the event two rotors are used on stationary member 1 they should be one-half revolution ahead of each other, and compression chamber 9 of the second rotor would be opposite surface 11 of the first rotor, giving a continuous working explosion, and rotors balancing each other. These and other changes in the form, proportion and minor details of construction may be resorted to without departing from the principle or sacrificing any of the advantages of the invention.

We claim:—

1. An engine embodying in combination with a supporting base, a stationary member, and a rotor arranged side by side and both of circular formation, the rotor being provided with a plane inner face, and the stationary member being formed in its inner face with an annular combustion chamber

- and an arcuate compression chamber, a stationary abutment in the combustion chamber having an inclined face, a power abutment slideable transversely of and carried by the rotor and working in said combustion chamber, a compressing abutment slideable transversely of the rotor and working in said compression chamber, and a tubular engine shaft on which said rotor is mounted 5 transversely movable, said tubular shaft forming an intake conduit for the explosive mixture, and the rotor being formed with a passage leading from the bore of said shaft to a port in the inner face of the rotor, and 10 also formed with a passage having inlet and outlet orifices arranged respectively to communicate with the compression and combustion chambers.
2. An engine embodying in combination 15 with a supporting base, a stationary member, and a rotor arranged side by side and both of circular formation, the rotor being provided with a plane inner face, and the stationary member being formed in its inner face with an annular combustion chamber and an arcuate compression chamber, a stationary abutment in the combustion chamber having an inclined face, a power abutment slideable transversely of and carried by the rotor and working in said combustion chamber, a compressing abutment slideable transversely of the rotor and working in said compression chamber, a tubular engine shaft on which said rotor is mounted 20 movable transversely, said tubular shaft forming an intake conduit for the explosive mixture, and the rotor being formed with a passage leading from the bore of said shaft to a port in the inner face of the rotor, and 25 also formed with a passage having inlet and outlet orifices arranged respectively to communicate with the compression and combustion chambers, and compression retaining rings 30 concentric with said shaft, arranged at the outer and inner sides of the combustion chamber, and working in annular grooves in the meeting faces of the stationary member and the rotor, and expansion compensating means for holding the rotor yieldingly 35 against the stationary member.
4. An engine embodying in combination 40 with a supporting base, a stationary member and a rotor arranged side by side and both of circular formation, the rotor being provided with a plane inner face, and the stationary member being formed in its inner face with an annular combustion chamber and an arcuate compression chamber, a stationary abutment in the combustion chamber having an inclined face, a power abutment slideable transversely of and carried by the rotor and working in said combustion chamber, a compressing abutment slideable transversely of the rotor and working in said compression chamber, a tubular engine 45 shaft on which said rotor is mounted movable transversely, said tubular shaft forming an intake conduit for the explosive mixture, and the rotor being formed with a passage leading from the bore of said shaft to a port in the inner face of the rotor, and 50 also formed with a passage having inlet and outlet orifices arranged respectively to communicate with the compression and combustion chambers, and compression retaining rings 55 concentric with said shaft, arranged at the outer and inner sides of the combustion chamber, and working in annular grooves in the meeting faces of the stationary member and rotor.
3. An engine embodying in combination 60 with a supporting base, a stationary member and a rotor arranged side by side and both of circular formation, the rotor being provided with a plane inner face, and the stationary member being formed in its inner face with an annular combustion chamber and an arcuate compression chamber, a stationary abutment in the combustion chamber having an inclined face, a power abutment slideable transversely of and carried by the rotor and working in said combustion chamber, a compressing abutment slideable 65
- transversely of the rotor and working in said compression chamber, a tubular engine shaft on which said rotor is mounted movable transversely, said tubular shaft forming an intake conduit for the explosive mixture, and the rotor being formed with a passage leading from the bore of said shaft to a port in the inner face of the rotor, and 70 also formed with a passage having inlet and outlet orifices arranged respectively to communicate with the compression and combustion chambers, compression retaining rings concentric with said shaft, arranged at the outer and inner sides of the combustion 75 chamber, and working in annular grooves in the meeting faces of the stationary member and the rotor, and expansion compensating means for holding the rotor yieldingly 80 against the stationary member.
4. An engine embodying in combination 85 with a supporting base, a stationary member and a rotor arranged side by side and both of circular formation, the rotor being provided with a plane inner face, and the stationary member being formed in its inner face with an annular combustion chamber and an arcuate compression chamber, a stationary abutment in the combustion chamber having an inclined face, a power abutment slideable transversely of and carried by the rotor and working in said combustion chamber, a compressing abutment slideable transversely of the rotor and working in said compression chamber, a tubular engine 90 shaft on which said rotor is mounted movable transversely, said tubular shaft forming an intake conduit for the explosive mixture, and the rotor being formed with a passage leading from the bore of said shaft to a port in the inner face of the rotor, and 95 also formed with a passage having inlet and outlet orifices arranged respectively to communicate with the compression and combustion chambers, compression retaining rings 100 concentric with said shaft, arranged at the outer and inner sides of the combustion chamber, and working in annular grooves in the meeting faces of the stationary member and rotor, expansion compensating 105 means for holding the rotor yieldingly against the stationary member, and means of creating a spark in the combustion chamber to start explosion and an exhaust port for release of burned gas.
